FLOOR COVERING SEAM PROTECTOR

Eugene F. Rowley, Turlock, Calif.

Application March 8, 1932, Serial No. 597,619

1 Claim. (Cl. 20—74)

The present invention relates to a floor covering seam protector and has for its primary object to provide, in a manner as hereinafter set forth, novel means for preventing damage to the edges 5 of sheets of floor covering, such as linoleum, while at the same time permitting expansion and contraction of said sheets.

Other objects of the invention are to provide a floor covering seam protector embodying a 10 novel construction, combination and arrangement of parts through the medium of which curling of the marginal portions of the sheets of floor covering will be prevented, and the accumulating of dirt and other matter between the opposed 15 edges of the sheets will be eliminated.

Other objects of the invention are to provide a floor covering seam protector which will be simple in construction, strong, durable, efficient and reliable in use, attractive in appearance and 20 which may be manufactured and installed at low cost.

All of the foregoing and still further objects and advantages of the invention will become apparent from a study of the following specification, taken in connection with the accompanying drawing wherein like characters of reference designate corresponding parts throughout the several 25 views, and wherein:—

Figure 1 is a view in top plan of a floor covering seam protector constructed in accordance with the present invention.

Figure 2 is a view in vertical section, taken substantially on the line 2—2 of Figure 1.

Figure 3 is a fragmentary detail view in perspective showing a portion of the supporting rib.

Referring now to the drawing in detail, it will be seen that the reference numeral 1 designates a portion of a floor having mounted thereon the floor covering, the adjacent portions of two sheets 40 of which are designated by the reference numeral 2, the opposed edges of the sheets 2 are separated from each other to provide the space 3.

The embodiment of the protector constituting the present invention which is illustrated in the drawing comprises a strip 4 of any suitable material, preferably metal, of a width sufficient to bridge the space 3 and overlap the adjacent marginal portions of the floor covering sheets 2. The strip 4 is formed to provide the beveled, downturned edges 5 which are engageable with the sheets 2.

The strip 4 is mounted on a supporting rib 6 which rests on the floor 1 between the sheets 2. The supporting rib 6 may, if desired, be secured 55 in any suitable manner to the strip 4 or said sup-

porting rib may be integral with the strip 4. As illustrated, the supporting rib 6 is provided with the spaced openings 7 for the passage of securing elements. Nails 8 are driven through the strip 4 and the supporting rib 6 into the floor 1 for securing the protector in position. Of course, any suitable securing elements other than nails, such as screws, may be used for this purpose.

The supporting rib 6 is of thickness slightly greater than the thickness of the sheets 2 in order 65 that the downturned, beveled edges 5 only of the strip 4 will contact with the sheets. This is illustrated to advantage in Figure 2 of the drawing.

It will thus be seen that the space 3 between the sheets 2 is effectively closed against the entrance of dirt and other foreign matter, at the same time permitting movement of the edges of the sheets toward or away from each other. The downturned longitudinal marginal portions of the strip 4 which terminates in the beveled edges 5 75 present only a slight obstruction to the feet of persons walking on the floor, thereby substantially preventing tripping, in addition to preventing the entrance of dirt between the strip and the sheets of floor covering and lending a 80 neat and attractive appearance to the protector.

It is believed that the many advantages of a floor covering seam protector constructed in accordance with the present invention will be readily understood, and although the preferred embodiment of the invention is as illustrated and described, it is to be understood that changes in the details of construction and in the combination and arrangement of parts may be resorted to which will fall within the scope of the invention as claimed.

What is claimed is:—

A floor covering seam protector comprising an elongated, substantially flat resilient metallic strip of a width sufficient to bridge the space between 95 two sheets of floor covering and overlap the adjacent marginal portions of said sheets, a supporting rib extending longitudinally beneath the strip and engaged with the floor between the sheets of covering, securing elements extending 100 through the strip and the supporting rib and anchored in the floor, the longitudinal marginal portions of the strip being down-turned and terminating in bevelled edges engageable with the floor covering, the supporting rib being slightly 105 greater in thickness than the floor covering.

EUGENE F. ROWLEY.
